UNITED STATES PATENT OFFICE.

WILLIAM W. HAYS, OF BUNKER HILL, ILLINOIS.

FRUIT-GATHERER.

SPECIFICATION forming part of Letters Patent No. 424,645, dated April 1, 1890.

Application filed August 16, 1889. Serial No. 321,031. (No model.)

To all whom it may concern:

Be it known that I, WILLIAM W. HAYS, a citizen of the United States, residing at Bunker Hill, in the county of Macoupin and State of Illinois, have invented certain new and useful Improvements in Fruit-Gatherers; and I do hereby declare the following to be a full, clear, and exact description of the invention, such as will enable others skilled in the art to which it appertains to make and use the same.

My invention relates to certain novel features involved in the construction of a fruit-gathering device, the object of which is to enable the operator to stand upon the ground and reach upward among the limbs of a tree and gather the fruit therefrom, and, while it is especially applicable to gathering apples without bruising them in any way, it is also equally well adapted to gathering various kinds of fruit.

Proceeding now to describe the various parts forming my improved fruit-gatherer, attention is called to the accompanying drawings, in which similar letters of reference designate corresponding parts in all the views.

Figure 1 is a perspective view showing the jaws partly closed. Fig. 2 is a central longitudinal section showing the jaws open. Fig. 3 is a view of the device used in opening and closing the jaws separated from the other parts. Fig. 4 shows how the movable knife is attached to the jaw.

Calling attention by letter to the several parts of the gatherer, A is the body proper, which is preferably formed by a hollow tube of a suitable size bent at its upper end at graduated angles, so as to form the elbow, as shown, while upon the inner side of such elbow is to be attached the housing B for the spring c and its accompanying casing C, which is properly suspended in said housing by axle d, which is firmly secured to the sides of the housing, so as to form an axle for casing C, arranged to turn upon said axle.

Within the casing C is arranged the spiral spring c, the inner end of which is secured to the axle, while the outer end is secured to the inner side of the rim of casing C. This spring, arranged as stated, is for the purpose of assisting in operating the jaws, as will hereinafter be shown.

Holding a transverse position with the body

proper is the outer jaw E, which consists of a thin piece of steel or other suitable material, the greatest width of which represents 55 the sextant of a circle, though this width may be increased or diminished, as preferred, while the general outline of said jaw is such that it will snugly coincide with and fit into the mouth of body A. The inner jaw D is 60 formed in similar manner and both are diametrically journaled to the sides of the mouth of body A, so that both of such jaws will have a position transversely with the body. To the inner jaw I attach the movable knife F, which 65 is formed to coincide with the convex surface or jaw D, and is secured thereto by rivets f f. A stationary knife may be secured to the other jaw, or the jaw may be made of a suitable metal, so that the inner edge thereof may 70 be sharpened. The ends of jaw E are properly connected by the semicircular loop e, to the middle of which is attached the operating-pitman e', extending inwardly and pivotally attached to the periphery of the casing C, as 75 indicated by l, as by such means the outer jaw is operated. At a point m opposite the place to which is attached pitman e' on the periphery of casing C, I attach in like manner pitman d', which shall reach outwardly 80 toward the lower point of the movable knife F, secured to the jaw D, as shown, and by such means operate said jaw and knife. Three parallel slots i i are provided in the knife F, arranged to engage with stationary rivets f f, 85 projecting from the jaw D, by the enlarged heads of which the said knife is held on said jaw in such a manner as to enable the knife F to have a sliding or vibrating motion, the object of such movement being to give a 90 snapping action to said knife when in use. At the point l, to which is attached pitman e', I also secure the inner end of chain I, which is arranged to follow the periphery of casing C downward and reach sufficiently out of the 95 housing B to form a connection with operating-rod J. Before the pistons are attached to the periphery of casing C a proper degree of tension is to be given to said casing by means of the spring c therein inclosed, and it 100 will be seen that when the chain is drawn downward such casing will revolve upon the stationary axle, and by such means operate the pitmen and the jaws thereunto attached—

that is to say, when the casing C is caused to have an inward motion the pitman e' will be drawn downward and thereby elevate the outer jaw, while the pitman d' in like manner will be forced outward and by such means give an outward movement to the jaw D and the knife secured thereto, when the latter will reach sufficiently past the edge of the former to properly sever the stem of the fruit.

10 When the downward pressure communicated to the chain I by rod J is removed, spring c will cause casing C to rotate backward to the starting-point and thereby give a reverse movement to the pistons, and by such means cause the jaws to open in readiness to repeat the operation. The rod J, attached to chain I, may be more conveniently operated by means of a lever properly secured to the side of the body A.

15 It will be seen that I have produced a simple, convenient, and effective means for accomplishing the purpose named, and I desire to call especial attention to the means employed for opening and closing the jaws, as I claim novelty both upon the means for opening and closing such jaws.

20 Having thus described my invention, what I claim as new, and desire to secure by Letters Patent, is—

1. A fruit-gatherer consisting of the body 30 A, the jaws D E, pivotally connected to the mouth of the body, the knife F, secured to the jaw D, the housing B on the body, the casing C in said housing, the pitmen d' e', having their lower ends secured to the casing C at 35 diametrically-opposite points and their upper ends connected with the knife and the jaw E, respectively, the volute spring within the casing and acting on the same to hold the knife and the jaw normally apart, the chain secured 40 to the casing, and the rod secured to the chain, as set forth.

2. The combination of the body, the jaws D E, pivoted to the mouth of the body, the rotary casing C, the loop e, secured to the jaw 45 E, the knife F, arranged upon the jaw D and having a series of longitudinal slots, the pins on said jaw engaging said slots, the pitmen connecting the knife and the loop e with diametrically-opposite points of the casing C, and 50 means for rotating said casing, as set forth.

In testimony whereof I affix my signature in presence of two witnesses.

WILLIAM W. HAYS.
